[57] **CLAIM**

The ornamental design for antenna for a satellite location measuring receiver, as shown and described.

DESCRIPTION

FIG. 1 is a top perspective view of antenna for a satellite location measuring receiver showing our new design;

FIG. 2 is a front elevational view thereof;

FIG. 3 is a right side elevational view thereof, a left side elevational view being a mirror image of the right;

FIG. 4 is a top plan view thereof;

FIG. 5 is a bottom plan view thereof;

FIG. 6 is a rear elevational view thereof; and,

FIG. 7 is a top perspective view thereof, the broken line showing of the remaining parts of an antenna being for illustrative purposes only and forming no part of the claimed design.

FIG. 1

FIG. 2

FIG. 3

FIG. 4

FIG. 5

FIG.6
